UNITED STATES PATENT OFFICE.

CHARLES A. BAILEY, OF CROMWELL, CONNECTICUT, ASSIGNOR TO THE
J. & E. STEVENS COMPANY, OF SAME PLACE.

DESIGN FOR A RANGE.

SPECIFICATION forming part of Design No. 23,707, dated October 16, 1894.

Application filed August 31, 1894. Serial No. 521,875. Term of patent 3½ years.

To all whom it may concern:

Be it known that I, CHARLES A. BAILEY, a citizen of the United States, and a resident of Cromwell, in the county of Middlesex and State of Connecticut, have invented a new and original Design for Ranges; and I do declare the following to be a full, clear, and exact description of the design, reference being had to the accompanying drawings, and to o letters of reference marked thereon, which form a part of this specification.

Figure 1 of the drawings is a representation of an elevation of the front side of range. Fig. 2 is an elevation of rear side of range. 5 Fig. 3 is a front elevation of range. Fig. 4 is a rear elevation of range.

This invention has relation to a certain new and useful design for ranges, and it consists in the novel form and configuration of parts, o all as hereinafter described and illustrated in the accompanying drawings.

Referring to the drawings, it will be observed that the general form of the body A as viewed in side and end elevation, and in 5 plan, is rectangular, with a depending curtain flange B at the base, and an overhanging top plate.

The rear portion C of the body, when viewed in plan, forms an even continuation of the o body, but when viewed in side elevation, is seen to form an offset from the base, its bottom line or wall having a double, upward curve. At the opposite end of the body is a horizontal hearth-projection G having a flat 5 surface, and slightly beveled lateral and front edges.

The curtain flange B extends entirely around the base, and has a leg extension B' at each angle. Said flange is ornamented by o a raised vine and flower figure, wherein the representation of the vine is wound alternately above and below the representations of flowers in series.

The rear side of the body A is ornamented by a large, fan-shaped figure D, in relief, with 45 a smaller figure of similar character in each lower corner. The corresponding surface of extension C has thereon a raised figure somewhat in imitation of a door with beveled faces.

The front end of the range, above the projection G has a door shaped figure H in relief thereon, with openings h at its lower portion.

The front side of the range, above the curtain flanges has a raised figure k thereon, below its small door K, and above this figure 55 and the door is a raised bar l, which is curved downwardly to meet the projection G. The small door K is ornamented with a rectangular figure L on its face, such figure inclosing four raised bars or arms radiating from the 60 four angles of a small central rectangle, and extending to the four corners of the figure. Around the said figure L are smaller raised figures.

The large or oven door M is ornamented by 65 four broad plane bars, forming a rectangle m, having an inner border of scroll-work and an outer border composed mainly of small points. The portion C on this side has a raised projection N formed in imitation of 70 the small door K. The rear end of said projection has thereon a series of raised bars N, radiating from a common center, and the lower curved wall of said extension has a series of parallel narrow openings.

Having thus described my invention, what I claim as new, and desire to secure by Letters Patent, is—

The design for a range substantially herein shown and described.

In testimony whereof I affix my signature in presence of two witnesses.

CHAS. A. BAILEY.
